UNITED STATES PATENT OFFICE.

VICTOR MILWARD, OF REDDITCH, COUNTY OF WORCESTER, ENGLAND.

MACHINE FOR POLISHING NEEDLES.

SPECIFICATION forming part of Letters Patent No. 236,904, dated January 25, 1881.

Application filed July 19, 1880. (No model.) Patented in England October 27, 1875.

To all whom it may concern:

Be it known that I, VICTOR MILWARD, of the firm of Henry Milward & Sons, of Redditch, in the county of Worcester, England, 5 needle and fish-hook manufacturers, a subject of the Queen of Green Britain, have invented certain new and useful Improvements in Machinery for Polishing Needles, (for which I have received Letters Patent in England, No: 10 3,725, dated October 27, 1875,) of which the following is a specification.

My invention consists of the construction and combinations hereinafter described of the parts of machinery for polishing needles.

15 The polishing machinery consists of a series of slow-rotating carrying-rollers, situated side by side, by which the needles are carried through the machine, in combination with a reciprocating carrying-plate or table sliding 20 backward and forward at right angles to the advancing motion of the needles, for supporting and rotating the needles, and with a series of polishing rollers or buffs for polishing the needles. The acting portions of the polishing-rollers work through slots in the carrying-plate, a polishing-roller being situated between two feeding-rollers. By the operation 25 of the feeding-rollers, reciprocating plate or table, and polishing-rollers the needles are 30 carried through the machine, rotated, and polished.

I feed the needles to the front pair of feeding-rollers by means of an automatic feeder, consisting, essentially, of a reciprocating hopper, in which the needles, in layers, are placed. By the forward motion of the reciprocating hopper the bottom layer of needles is carried through a slot at the front of the feeder, and is fed between a roller and a narrow bar or 40 plate with a knife-edge, fixed to the base-plate of the hopper, onto the reciprocating plate of the polishing-machine.

Having explained the nature of my invention, I will proceed to describe, with reference 45 to the accompanying drawings, the manner in which the same may be carried into effect.

Figure I represents in plan, Fig. II in transverse vertical section, and Fig. III in side elevation, partly in longitudinal section, a machine for polishing needles constructed according to my invention.

The automatic feeder constituting part of my invention is represented in Fig. I combined with the polishing-machine; but the said feeder will be hereinafter fully described 55 with reference to the enlarged views of the said feeder shown in Figs. IV, V, and VI.

The same letters of reference indicate the same parts in Figs. I, II, and III.

a is the bed-plate of the machine, to which 60 the uprights b b are affixed. These uprights, besides carrying the polishers or buffs, also support the frame c² c², in which the series of carrying-rollers c d e f g h i j k l² is supported. The ends of the said carrying-rollers turn 65 freely in their bearings, and have a slow rotary motion given to them in the manner hereinafter described. The said feeding-rollers are situated side by side, as represented in the drawings.

l m n o are four polishing rollers or buffs, situated below the said feeding-rollers, a polishing-roller being situated between two feeding-rollers. (See the section, Fig. II.) The polishing rollers or buffs l m n o work in centers in the 75 ordinary way, and are driven at a high velocity by guts or bands passing over the driving-pulleys l² m² n² o².

p is the reciprocating sliding plate or table on which the needles are supported as they 80 are carried through the machine, and by which, in conjunction with the feeding-rollers c d e f g h i j k l², a rolling motion is given to said needles. The said reciprocating sliding plate or table p works in a dovetail, p², on the bed-plate 85 of the machine, and has a slow motion given to it, the said plate or table p moving backward and forward at right angles to the advancing motion of the needles—that is, the said plate or table p moves sidewise to the 90 feeding and polishing rollers, or in the direction of the axes of the said rollers. Slots or openings are made in the reciprocating sliding plate or table p, through which slots the acting parts of the polishers or buffs l m n o work. 95 (See the cross-section, Fig. II.)

A is the feeding end of the machine, at which any desired kind of feeder may be applied; but I prefer to use the construction of feeder hereinafter described; and B is the delivering 100 end of the machine, at which the polished needles, as they issue from the last feeding or car-

rying roller, are received in a receptacle placed at the said end for that purpose.

The moving parts of the machine are worked by the following mechanism: The polishers or buffs $l m n o$ are driven by guts or bands working over the pulleys $l^2 m^2 n^2 o^2$, as before described. The feeding-rollers $c d e f g h i j k l^2$ are driven by worms $q q$ (or a long worm) on an axis passing across the machine, the said worms gearing with worm-wheels $r r$ on the ends of the said feeding-rollers. The shaft or axis of the worms $q q$ is driven from the driving-shaft s through the spur-gearing $t u x$.

The reciprocating sliding plate or table p is worked in the following way: On the driving-shaft s is a crank, r , upon the crank-pin r^2 of which the connecting rod or link r^3 works, the inner end of the said rod or link being jointed at r^4 to the reciprocating plate or table p , as best seen in Fig. III. I do not limit myself to the working of the plate or table p by a crank and connecting-rod, as represented, as other equivalent mechanism may be used.

The action of the machine is as follows: The needles to be polished are fed, by preference, by the automatic feeder represented at the end A to the first feeding-roller, d . The needles are received on the carrying or supporting reciprocating plate or table p , between which and the front pair of feeding-rollers, $c d$, they are seized and carried to the first polisher or buff, l , the needles having a rolling as well as an advancing motion given to them by the movement of the said sliding plate or table p under the rotating feeding-rollers $c d$. Before the needles leave the roller d of the front pair they are seized between the second pair of rollers, $e f$, and the carrying plate or table p , by which they are rotated and advanced to the second polisher or buff, m , and in like manner are carried in succession to the third and fourth polishers or buffs, n and o , and delivered by the last pair of feeding-rollers, $k l^2$, into a receptacle at the delivering end B of the machine. By the combined operations of the reciprocating plate or table p and feeding-rollers every part of the needles is, by the rolling and advancing motions which are communicated to them, brought under the operation of the several polishers or buffs before the said needles leave the machine.

The direction in which the needles are carried through the machine is indicated by the arrows in Figs. I and II. It will be readily seen by reference to the section Fig. II how the needles, before they leave one of the feeding-rollers, are seized by the next roller, so as to carry the needles through the machine.

Although I have represented a machine composed of ten feeding-rollers and four polishers or buffs, in combination with the reciprocating plate or table, yet I do not limit myself to that number of feeding and polishing rollers, as a greater or less number may be combined together in the manner represented.

The machine represented may be modified by making the plate or table on which the needles

are advanced and on which they are supported stationary and giving the frame supporting the carrying-rollers a to-and-fro motion. By the reciprocating motion of the feeding-rollers the needles on the fixed plate have a rolling motion given to them as they are carried through the machine.

My improved automatic feeder is represented in plan in Fig. I in combination with the polishing-machine, and detached, drawn to a larger scale, in Figs. IV, V, and VI, Figs. IV and V representing transverse sections, and Fig. VI an end elevation, of the said feeder. It consists of a reciprocating sliding hopper, a , in which the needles to be fed are contained, having a rising and falling front plate, a^4 , and a rotatory feeding-roller, b , working under the part c^2 of the fixed bed-plate c . The hopper a is filled with needles in layers, the said layers crossing the hopper in its shorter direction. The said reciprocating hopper a is fixed to the slide a^2 , which works in a dovetail on the bed-plate c . On the part c^2 is an incline, c^3 . The under side of the fixed part c^2 is situated at a higher level than the bed-plate c , so as to form a passage, e , between them, through which passage the needles from the hopper a are fed between the roller b and the under side of the said part c^2 . The movable front plate, a^4 , of the hopper travels up the incline c^3 on the part c^2 when the said hopper makes its advance motion to feed the needles. The said plate a^4 works independently of the other part of the hopper, and is pressed down by springs $a^5 a^6$. Those parts of the layers of needles in the hopper a (above the bottom layer, which is being fed to the feeding-roller b) situated at the front of the hopper also travel up the incline c^3 of the plate c^2 , and prevent obstruction to the feeding of the bottom layer of needles. In Fig. IV the hopper a is represented at the end of its back-stroke, the heads of a row of needles being represented bearing against the back plate, a^6 , of the hopper. By the advance of the hopper in the direction indicated by the arrow the lower layer of needles passes through the opening at e , and is seized between the rotatory roller b and the fixed plate c^2 , as illustrated in Fig. V, which represents the hopper at the end of its advance stroke, and by the motion of the said roller b the layer of needles is carried to the front pair of feeding-rollers of the polishing-machine. As the reciprocating hopper makes its back or return stroke in a direction contrary to that indicated by the arrow the bottom layer of needles in the hopper takes the place of that layer last fed, and so on, a layer of needles being fed forward at each advance stroke of the hopper. The return or back stroke of the hopper is effected by means of the arms $g g$, to which a rocking motion is given by the rocking shaft h under the feeder, the said rocking shaft h being worked by the lever i , acted upon by the cam k on the cam or driving shaft n . The upper ends of the rocking arms $g g$ are slotted, and

in the said slots the crank-pins l l , attached to the dovetail slide a^2 of the feeder, work. The advance stroke of the reciprocating hopper a is effected by coiled springs m , attached to the 5 rocking arms g g and to the fixed framing of the feeder. The cam-shaft n is driven by a gut or band passing over the pulley p^2 , and the feeding-roller b is driven from the said shaft n by the toothed wheels q^2 r^2 s^2 .

10 Having now described the nature of my invention and the manner in which the same is to be performed, I wish it to be understood that I claim as my invention—

15 1. Machinery for polishing needles in which the following parts are combined, namely: a series of slowly-rotating carrying-rollers, by which the needles are carried through the machine, a carrying plate or table for supporting and rotating the needles, and a series of 20 polishing rollers or buffs situated below the said carrying plate or table, through slots or open-

ings in which plate or table the acting portions of the polishing rollers or buffs work, the said carrying plate or table and carrying-rollers having the one a reciprocating motion with 25 reference to the other, and the several parts of the machine being arranged and operating substantially as hereinbefore described.

2. An automatic feeder for feeding needles to polishing-machines, consisting of a reciprocating sliding hopper having a rising and falling front plate, in combination with a fixed inclined part upon which the rising and falling front plate works, and a rotating feeding-roller, the several parts being constructed and 30 operating substantially as hereinbefore described.
